UNITED STATES PATENT OFFICE.

HARRY ULMER, OF PHILADELPHIA, PENNSYLVANIA, ASSIGNOR TO HARDWICK & MAGEE COMPANY, OF PHILADELPHIA, PENNSYLVANIA, A CORPORATION OF PENNSYLVANIA.

DESIGN FOR A CARPET OR SIMILAR ARTICLE.

Application filed December 8, 1923. Serial No. 7,980. Term of patent 3½ years.

To all whom it may concern:

Be it known that I, HARRY ULMER, a citizen of the United States, residing in Philadelphia, Pennsylvania, have invented a certain, new, original, and ornamental Design for a Carpet or Similar Article, of which the following is a specification, reference being had to the accompanying drawing, forming part thereof.

The figure is a face view of my new design for a carpet or similar article, the design illustrated being repeated through the length of the carpet or similar article.

I claim:

The ornamental design for a carpet or similar article, substantially as shown and described.

HARRY ULMER.
